FREIGHT HANDLING CRATE

Filed Sept. 27, 1928.

UNITED STATES PATENT OFFICE

JOHN J. FULLERTON, OF NORTH BERGEN, NEW JERSEY, ASSIGNOR TO FULLERTON TRUCKING COMPANY, OF NEW YORK, N. Y., A CORPORATION OF NEW YORK

FREIGHT-HANDLING CRATE

Application filed September 27, 1928. Serial No. 308,765.

This invention relates to a crate for handling freight and is more particularly designed for handling hollow-tile, brick, or similar articles.

5 One object of the invention is to provide a crate in which tile, brick or other articles may be piled, and the loaded crate may be handled as a unit, the tile remaining thereon to the point of ultimate use thereof, such 10 as a building.

Another object is to provide a crate having ends which are rigid when secured in upright position and which may be easily folded upon the crate when the same is unloaded.

15 Another object is to provide a crate which is light in weight yet durable and strong.

These and further objects will be apparent from the following description taken in connection with the accompanying drawings,

20 wherein

Fig. 1 is a side elevation of the crate showing the method used in loading the same,

Fig. 2 is a top plan of the crate,

Fig. 3 is a section on line 3—3 of Fig. 1.

25 Fig. 4 is a section on line 4—4 of Fig. 3.

Referring to the drawings, the base of the crate is formed of two structural steel T members 1, two side members 2 which are angle irons and end members 3 which are substantially Z-shaped. The flanges of the T members 1 and the angle irons 2 are secured to the lower flange of the Z members 3 by riveting or welding, the clearance between members 1 and 2 being such that the articles to be handled by the crate may be received between the upright flanges thereof and rest upon the lower flanges thereof, as seen in dotted lines in Fig. 3. In the crate as illustrated,

30 the clearance between adjacent upright flanges is slightly more than 12 inches to thereby accommodate 12 inch hollow tile. However, it will be understood that this clearance may be suitably varied to accommodate any other size of article to be handled.

45 The crate has foldable ends in order that the load piled thereon may be more secure. Each end is formed of an angle iron 4 having its ends bent upwardly, one flange of the angle being cut to allow the bending, and the

cut flange being preferably welded together. The upwardly bent portions of angle 4 are connected by straps 5.

Each of these ends is secured to the bottom of the crate by means of two sets of links 6 pivotally secured by pins 7 to the outside of angle irons 4 and to angle irons 2 of the bottom. Each pair of links is pivotally connected by pivot pins 8, whereby the ends may be folded down on the bottom as seen in dotted lines in Fig. 1.

55 In order that the ends may not slip out of their vertical positions, dowel pins 9 are secured to the lower sides of angle irons 4. These dowel pins project into corresponding 60 holes in the upper flange of Z members 3.

65 As will be seen from Fig. 1, the articles to be handled, such as hollow tile, are piled between adjacent T irons 1 and angles 2, and one tier of such articles is piled on top of 70 angle iron 4 of each folding end. The Z iron 3 is made approximately one half the depth of each article to be handled, whereby the end tier of articles is staggered with respect to the adjacent tier. By this means 75 the folding ends are braced and the entire load is securely held in position.

70 The crate is adapted to be loaded and handled as a loaded unit by mechanical handling devices without unloading the same. The 80 handling device is placed under the overhanging flanges of the Z members 3 at each end and the loaded crate is thus picked up. No lifting strain is thus placed on the folding ends of the crate.

85 The crate may be handled by a carrying frame such as disclosed in my copending application 245,772, filed January 10, 1928, or any similar mechanism.

It will be understood that the invention is 90 not limited to the details of construction except in so far as set forth in the accompanying claims.

I claim:

1. A crate for handling tile or other articles piled in stacks, including a rigid bottom, and foldable ends secured to said bottom by means of links pivoted to said ends and to said bottom.

2. The structure as set forth in claim 1 100

wherein said folding ends are held in vertical position with respect to said bottom by means of dowel pins.

3. A crate for handling tile or other articles piled in stacks comprising a rigid bottom having overhanging flanges on two sides thereof, the said flanges being spaced vertically above said bottom, and foldable ends pivoted to said bottom and having bases 10 which rest upon said overhanging flanges when said sides are in vertical position.

4. The structure as in claim 3 wherein cooperating dowel pins and openings are provided between said overhanging flanges and the bases of said ends resting thereon.

5. The structure as in claim 3 wherein bases of said foldable ends are of such size as will support one tier of the tile to be handled by said crate.

6. A crate for handling tile or other articles piled in stacks, including a plurality of spaced members, said members having flanges projecting toward each adjacent member, to receive thereon the articles to be handled, the projecting flanges lying in a common horizontal plane, and a Z iron securing the ends of said members in spaced relation, and having its base and top flanges parallel to the plane of said projecting flanges of the spaced members.

7. A crate for handling tile or other articles piled in stacks, including a bottom formed of a plurality of longitudinal members arranged in spaced relation, said members having projecting flanges extending toward adjacent members to receive thereon, the articles to be handled, Z irons connecting the ends of said longitudinal members, the flanges of said members resting on and being secured to an inwardly projecting lower flange of said Z irons, and foldable ends secured to said bottom by links, the bases of said foldable ends resting on said outwardly projecting flange of said Z iron when said ends are in vertical position.

8. A crate for handling tile or other articles piled in stacks, including a plurality of spaced members, said members having flanges projecting toward each adjacent member to receive thereon the articles to be handled, the projecting flanges lying in a common horizontal plane, and means comprising Z irons for securing the ends of said members in said spaced relation, the flanges of said members resting on and being secured to the lower inwardly projecting flanges of said Z irons.

In testimony whereof, I affix my signature.
JOHN J. FULLERTON.
